VONDON D. SIBLEY, OF PORT HAMMOND, CANADA, ASSIGNOR OF ONE-HALF
TO PETER McTAVISH, OF VANCOUVER, BRITISH COLUMBIA, CANADA.

SNAP-HOOK.

SPECIFICATION forming part of Letters Patent No. 733,921, dated July 14, 1903.
Application filed April 29, 1903. Serial No. 154,871. (No model.)

To all whom it may concern:

Be it known that I, VONDON D. SIBLEY, a citizen of the Dominion of Canada, residing at Port Hammond, in the Province of British Columbia, Canada, have invented a new and useful Improvement in Snap-Hooks, of which the following is a specification.

My invention relates to an improved snap-hook designed so as to be simple and cheap to manufacture and to combine a maximum of strength with a minimum of weight. To attain these objects, I make the hook from one piece of wire, without any further work on it than that of cutting and bending. By such construction I avail myself of the greater weight-for-weight strength of wire than malleable cast-iron or drop-forgings, of which material these articles are commonly made, with the further advantage that the device has in its own structure the necessary resilience to effect the closing of the hook without the requirement of hinge-joints and independent springs.

Another point in my design is the reinforcement of the hook end and the support of the strain on it from opposite sides, so that the flexure of one side checks that of the other.

The particular construction of my device is fully described in the following specification, reference being made to the drawings which accompany it, in which—

Figure 1 is a perspective view of the hook in its normal or closed position; Fig. 2, a similar view of it when opened by the application of finger-pressure in the direction of the arrows *a a*; Fig. 3, a side elevation of the hook portion closed, and Fig. 4 a similar view of the same open.

The attaching-eye of the device is formed by a double-coiled loop 2, and the wire is thereafter crossed to opposite sides, as 3 and 4, and is then turned downward in slightly-diverging lines, one side, 3, being toward the end bent inward in single wire and curved back to form a reverse hook 5, the center of which is on the center line of the device—*i. e.*, in the line of strain. The opposite side 4 is bent to the same general conformation, but of course reversed, and the lower end is of double wire, enabling the hook 5 of the other member to pass freely between the dual mem-

bers 6. The end 6 is bent downward, as at 7, and angled back toward the center line, enabling the crossover 7^a or end of the loop to clear the movement of 5 and form at the same time an entering angle to guide to the opening when clasping. (See *e* in Figs. 2 and 4.)

The doubled-up end of 6 is wound around the member 4 at 8 and is made into a cross-loop 10, within which the member 3 is free to move, as in a guide, and at the outer end of which it is checked when in its normal position, the end of the wire being thereafter secured to 4 by a turn 9.

In its normal position closed (see Figs. 1 and 3) the outward spring of the wire keeps the member 3 against the outer end of the guard-loop 10, in which positions the hook portions 5 and 6 of the opposing members 3 and 4 coincide and form an inclosing ring which will securely retain anything placed within it and will offer not only the triple strength of the material to any pull, but owing to the flexure under strain of each portion being in opposite directions outward the tendency to straighten in one hook will be checked by the similar tendency in the opposite direction of the other.

The doubling of one hook 6 to include the other, 4, also enables them to afford mutual support to one another under any tendency to spring or yield laterally.

When 3 and 4 are pressed together against the spring or resistance of the coil 2, as indicated by the arrows *a a*, (see Figs. 1 and 2,) the hooks 5 and 6 are opened and a ready entrance is afforded, the outside of the hook 5 and downwardly-turned end 7 of the hook 6 (see Figs. 2 and 4) combining to form a converging entrance-guide (see *e* in Figs. 2 and 4) which facilitates attaching the hook to any suitable connection.

A careful consideration of the points mentioned will satisfy any competent person that the hook possesses elements of strength beyond what would at first sight appear, while it is securely locked on anything it is connected to, which can escape only by the bending or fracture of the members. The particular manner in which it is constructed from one piece of wire and the design which util-

izes the coil of the eye 2 to give an efficient and durable spring are features which alone render my invention a novel and useful one.

I therefore declare that what I claim as new, 5 and desire to be protected in by Letters Patent, is—

1. A wire snap-hook comprising a spring portion forming an eye-ring; opposing lever members forming continuations thereof, the 10 lower ends of which are formed into oppositely-bent hook members, one being of double wire between which the other is designed to pass, the openings of such hook members being to the outer side in each, so that in the 15 normal or closed position, the opening of one is closed by the hook portion of the other; a loop secured to one of the lever members forming a lateral guide and check to the movement of the other, whereby the outward 20 spring tendency is limited and the combination of the double and the single hook forms a retaining-eye.

2. In a wire snap-hook having a spring-coil eye, opposing lever members terminating in

oppositely-bent hooks and a guide-loop to 25 check the opposing hooks in their outward spring movement, so that they will normally form a retaining-eye; the construction of one of the hooks of looped wire with a space between the loop to permit the passage of the 30 single hook, the end of the loop being bent back to form an entering-guide to within the hooks when the levers are pressed together and the retaining-eye opened.

3. In a wire snap-hook made from one piece, 35 the double-coil spring member 2, lever members 3 and 4, one having the single hook 5 and the other one the double hook 6, the downwardly-turned loop end 7, 7^a on the double hook and the guide and check loop 10. 40

In testimony whereof I have hereunto signed my name in the presence of two subscribing witnesses.

VONDON D. SIBLEY.
